UNITED STATES PATENT OFFICE.

FRIEDRICH DÖPPENSCHMITT, OF PFORZHEIM, GERMANY.

EXTENSIBLE TUBE FOR JEWELRY PURPOSES.

1,117,986.

Specification of Letters Patent.

Patented Nov. 24, 1914.

Application filed April 13, 1914. Serial No. 831,590.

To all whom it may concern:

Be it known that I, FRIEDRICH DÖPPENSCHMITT, a citizen of the German Empire, residing at Pforzheim, in Germany, have 5 invented certain new and useful Improvements in Extensible Tubes for Jewelry Purposes, of which the following is a specification.

The object of this invention is to provide 10 an improved form of extensible tube for bracelets and other jewelry purposes, and the invention essentially consists in forming a tube of annular wire helices enmeshed with each other, inclosing a coiled spring 15 or springs.

The invention is illustrated in the accompanying drawing, in which—

Figure 1 shows a portion of the tube, contracted, partly in section on the line 20 $q-q$ of Fig. 3; Fig. 2 shows the same piece of tube, extended, also partly in section, and Fig. 3 is a cross section thereof. Figs. 4 and 5 are cross sections, showing two other forms of construction.

Referring in the first instance to the construction shown in Figs. 1 to 3, a designates a tube formed of flexible wire helices 25 screwed into each other. To serve as a bracelet or the like, this tube forms a closed 0 ring. Within this tube are two coiled springs b , preferably attached inside at the ends c . When the tube a has been extended, as shown in Fig. 2, the coiled springs are likewise extended, and serve to contract the 35 tube again when the pull ceases. The wire helices forming the tube a have a kink or indentation between the two springs b .

Fig. 4 shows an extensible tube a^1 , with a single coiled spring b^1 , and Fig. 5 shows a tube a^2 , with three coiled springs b^2 and 40 two indentations, between the central spring and the two side springs.

The wires forming the extensible tube may be enmeshed with each other in other ways than that illustrated in Figs. 1 and 2, 45 and may be plain or ornamented with a pattern.

What I claim as my invention and desire to secure by Letters Patent of the United States is:—

1. The combination, for jewelry purposes, of an extensible tube, formed of a series of annular wire helices enmeshed with each other, and a coiled spring in said tube adapted to contract same.

2. The combination, for jewelry purposes, of an extensible tube, formed of a series of annular wire helices enmeshed with each other, and a plurality of coiled springs in said tube adapted to contract same.

3. The combination, for jewelry purposes, of an extensible tube, formed of a series of annular wire helices enmeshed with each other, and a plurality of coiled springs in said tube adapted to contract same, the wall 65 of said tube being indented between said springs.

In witness whereof I have signed this specification in the presence of two witnesses.

FRIEDRICH DÖPPENSCHMITT.

Witnesses:

S. S. BERGER,
G. GRIZEZ.
